RECEIVER AND ACTION ASSEMBLY FOR FIREARMS

Thomas R. Robinson, Jr., Newton, Conn., assignor to The Marlin Firearms Company, New Haven, Conn., a corporation of Connecticut

Application November 28, 1947, Serial No. 788,530

12 Claims. (Cl. 42—16)

1

The present invention relates in general to firearms and more especially to the receiver, breech-bolt and trigger-plate assembly of an automatic self-loading firearm.

An object of the invention is to provide an improved receiver and breech-bolt assembly for insuring reliable and uniform operation of a firearm.

A further object of the invention is to provide improved breech-bolt guide-means in the receiver of a firearm whereby the reliable and uniform operation of the breech-bolt is assured, irrespective of the accumulation of adventitious material within the receiver.

A still further object of the invention is to provide the receiver of a firearm with improved breech-bolt guide-means for reducing frictional drag between the breech-bolt and the interior wall of the receiver and for insuring a uniform cycle of operations.

A still further object of the invention is to provide the receiver of a firearm with improved breech-bolt guide-means which is of simple and economical construction and which is adapted to provide means for attaching a trigger-plate to the underside of the receiver.

With the above and other object in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a side elevation of the receiver of an automatic self-loading firearm including a trigger-plate mounted on the underside thereof and a fragmentary portion of the barrel;

Fig. 2 is a side elevation in section of the receiver of Fig. 1 on a vertical plane through the longitudinal axis thereof;

Fig. 3 is an end elevation in section on line 3—3 of Fig. 1;

Fig. 4 is a perspective view of the receiver of the firearm shown in Fig. 1; and

Fig. 5 is a perspective view of the trigger-plate which is secured to the underside of the receiver, as shown in Fig. 1.

Referring to the drawings which, for the purposes of illustration, show the invention as embodied in an automatic self-loading firearm of the type more fully disclosed in my co-pending applications Ser. No. 766,663, filed August 6, 1947, patented November 30, 1948, as Patent No.

2

2,454,835, and Ser. No. 786,232, filed November 15, 1947, patented December 28, 1949, as Patent No. 2,492,814, and comprising, in the main, a receiver indicated generally at 15, a barrel 16 fixedly secured to the forward end thereof and a receiver-element such as, for example, a trigger-plate 17 attached to the underside of the receiver.

The latter comprises a substantially-cylindrical member preferably formed from a suitable length of tubular steel stock (see Fig. 4), the rear end of which is closed by a receiver-plug 18. The barrel 16 is adapted to be secured in the forward restricted end of the receiver, the restriction of which is provided, for example, by a relatively-thick-walled bushing 19 welded or otherwise secured therein so as to divide the interior of the receiver into a forward chamber 20 of reduced diameter and a concentric axially-aligned rearward chamber 21. The latter is hereinafter referred to as the breech-bolt guide-chamber, the inside diameter of which corresponds substantially to the inside diameter of the receiver-tube. Although a receiver comprising a tubular-member having a cylindrical bushing inserted in one end thereof to form a composite breech-bolt chamber of two diameters is a highly satisfactory and economical construction, it will be appreciated that it is within the purview of the invention to form the receiver, including the forward and rearward chambers 20 and 21 respectively, from a single piece of stock in any well known and approved manner.

Formed in the underside or bottom of the breech-bolt guide-chamber 21 of the receiver are 35 a plurality of apertures, indicated generally at 22, which communicate with the trigger-plate 17 in which the fire-control mechanism (not shown) is adapted to be mounted. A suitable ejection-port 23 is provided in the right-hand side of the receiver and comprises a substantially-longitudinal slot communicating with the forward chamber 20 of the receiver.

Mounted to reciprocate longitudinally in the composite breech-bolt chamber of the receiver, is a breech-bolt, indicated generally at 24, which as shown in Figs. 1 and 2 comprises a substantially-cylindrical rear end-portion 25 adapted to be slidably supported in the breech-bolt guide-chamber 21 of the receiver by suitable guide-means, as hereinafter described; and a substantially-cylindrical front end-portion 26 of reduced diameter adapted to make a smooth sliding fit in the forward chamber 20 of the receiver. The breech-bolt may be formed from two separate cylindrical elements of different external dia-

ters, the element of smaller external diameter being secured by a welded joint or similar fastening-means in the forward end of the element of larger diameter and in axial alignment therewith. Although a two-piece bolt is quite successful both from the standpoint of operation and economy of manufacture, it will be appreciated that the breech-bolt may be turned out of a single piece of stock. The breech-bolt is adapted to be operated manually by means of a handle 21 which is detachably secured thereto and projects through the ejection-port 23 of the receiver, the handle being cooperatively associated therewith to prevent rotation of the bolt in the chamber, as more fully described in the applications above identified. Other details of the breech-bolt such as, for example, its firing-pin (not shown), as well as details of the action mechanism, including the firing-plunger and sear, are the subject-matter of the aforementioned applications and, hence, the present description is not burdened with a description of these elements.

Referring particularly to Figs. 2 and 3, the breech-bolt and more especially the enlarged rear end-portion 25 thereof is adapted to be supported and guided in the breech-bolt guide-chamber 21 of the receiver by improved guide-means comprising ribs 28 which extend longitudinally of the breech-bolt guide-chamber and are spaced circumferentially around the inner wall thereof. In this connection, it will be noted more especially from Fig. 3 that the diameter of the enlarged rear end-portion 25 of the breech-bolt is appreciably less than the inside diameter of the breech-bolt guide-chamber 21, as a consequence of which the guide-ribs 28 constitute the sole supporting-means for the rear end-portion of the breech-bolt. In the particular embodiment of the invention illustrated in the drawings, three such guide-ribs are shown, one rib being at the top of the chamber in a vertical plane through the longitudinal axis thereof while the two remaining guide-ribs are formed on opposite sides respectively of the chamber and at angles of substantially 120° with respect to the top guide-rib and to each other. Each guide-rib is provided with a longitudinal bearing surface 29 which is elevated above the circumferential plane of the inner wall of the guide-chamber and which comprises a concave substantially-cylindrical surface of revolution, the radius of which corresponds substantially to the radius of the enlarged rear end-portion 25 of the breech-bolt. In the embodiment of the invention shown herein, the total area of the bearing surfaces 29 of the guide-ribs is as little as twelve-and-one-half per cent of the circumferential area of the breech-bolt guide-chamber, as a consequence of which the breech-bolt reciprocates longitudinally in the chamber with a minimum frictional drag. Moreover, since the breech-bolt is supported in spaced relationship to the interior wall of the breech-bolt chamber, any likelihood of the breech-bolt being fouled by the accumulation of adventitious material in the receiver, is effectively obviated. Although the specified ratio of the total area of the bearing surfaces of the guide-ribs to the circumferential area of the chamber has been found highly satisfactory, it will be understood that this ratio is by way of example only and that it is within the purview of the invention both to increase or decrease the area of the bearing surfaces within limits consistent with the satisfactory operation of the firearm.

The circumferentially spaced guide-ribs 28 of 75

the breech-bolt guide-chamber may comprise narrow substantially-solid bars or strips of metal spot welded or otherwise secured on the inner wall of the chamber, but as shown especially well in Fig. 3, it is preferred, from the standpoint of economy, to form the ribs by a striking-in operation performed upon the exterior wall of the receiver longitudinally thereof and at circumferentially-spaced points on its perimeter. In this manner, the guide-ribs 28 are formed as integral in-struck portions of the receiver, the bearing surfaces 29 of which may be formed, for example, by passing a reamer or similar tool lightly along the inner convex edges thereof to form concave cylindrical surfaces of revolution. Simultaneously, the exterior wall of the receiver opposite the longitudinal in-struck guide-ribs is formed with longitudinal grooves 30. As shown especially well in Fig. 2, the forward ends of the guide-ribs 28 constitute abutments against which the rear end of the bushing 19 is seated in assembling the latter in the receiver.

The longitudinal exterior grooves 30 in opposite sides respectively of the receiver constitute means for attaching the trigger-plate 17 to the underside thereof. Referring more especially to Fig. 5, the trigger-plate comprises a substantially-U-shaped member having spaced parallel substantially-vertical sides 31, each of which is provided at its upper edge with an outwardly-turned flange 32, the inner face 33 of which, as shown particularly well in Fig. 3, constitutes a concave substantially-cylindrical surface of revolution adapted to conform to the curvature of the exterior wall of the receiver. Moreover, each flange is provided along its upper edge with an upwardly-projecting in-turned lip 34 which extends longitudinally thereof from the forward end of the trigger-plate rearwardly for substantially two-thirds of its length, each lip 34 being adapted to engage in one of the corresponding grooves 30 in the opposite sides of the receiver, the inherent flexibility of the side walls 31 of the trigger-plate serving to hold the lips 34 thereof resiliently in the corresponding grooves of the receiver. To further insure that the trigger-plate is attached to the receiver securely and against longitudinal movement with respect thereto, the concave flange-portions 32 of the trigger-plate may be fastened by spot welds 35 or equivalent fastening-means to the adjacent wall of the receiver.

By providing longitudinal circumferentially-spaced guide-ribs 28 on the inner wall of the breech-bolt chamber, relatively-large circumferential clearance-spaces are maintained between the periphery of the rear end-portion 25 of the breech-bolt and the inner wall of the guide-chamber, as a consequence of which the longitudinal reciprocating movement of the breech-bolt whether by recoil, spring or hand manipulation will be substantially free irrespective of the inclusion of adventitious material in the breech-bolt chamber. It will be evident too that since the guide-means engages the periphery of the breech-bolt only along longitudinal circumferentially-spaced areas thereof, the resulting circumferential clearance-spaces between the periphery of the breech-bolt and the inner wall of the chamber extend without material obstruction from front to back of the breech-bolt, thus precluding the formation of an air-cushion between the rear end of the breech-bolt and the forward end of the receiver-plug. Moreover, by providing guide-ribs having bearing surfaces of relatively-

small area, the frictional drag on the breech-bolt is reduced to a minimum value.

As a consequence of these characteristic features of the invention, the operation of the breech-bolt particularly in automatic self-loading firearms is reliable and uniform. In this connection, it should be pointed out that the adaptation of the invention to an automatic firearm is particularly desirable in order to eliminate variations in its operation cycle, but that the invention is equally adapted for use successfully with all firearms having a reciprocable longitudinally-sliding breech-bolt.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a firearm the combination including: a receiver having a breech-bolt chamber; breech-bolt guide-means on the inner wall thereof said guide-means comprising circumferentially-spaced parallel ribs extending longitudinally of said chamber; and a breech-bolt supported in said chamber by said ribs in relatively widely-spaced relationship to the inner wall of said chamber for longitudinal reciprocable movement in said chamber.

2. In a firearm the combination including: a receiver having a breech-bolt chamber; breech-bolt guide-means on the inner wall thereof said guide-means comprising circumferentially-spaced parallel ribs extending longitudinally of said chamber, and bearing-surfaces extending longitudinally of said ribs, said bearing-surfaces being concentric with respect to the longitudinal axis of said receiver; and a breech-bolt supported in said chamber on said bearing surfaces for longitudinal reciprocable movement in said chamber.

3. In a firearm the combination including: a receiver having a breech-bolt chamber; breech-bolt guide-means on the inner wall thereof said guide-means comprising circumferentially-spaced parallel ribs extending longitudinally of said chamber, and bearing-surfaces of substantially-equal area extending longitudinally of said ribs said bearing-surfaces being concentric with respect to the longitudinal axis of the said receiver and constituting in area substantially as little as twelve-and-a-half per cent of the corresponding inner circumferential area of said chamber; and a breech-bolt supported in said chamber on said bearing-surfaces for longitudinal reciprocable movement in said chamber.

4. In a firearm the combination including: a receiver having a breech-bolt chamber; breech-bolt guide-means on the inner wall thereof said guide-means comprising circumferentially-spaced parallel ribs consisting of metal struck inwardly from the exterior wall of said chamber and extending longitudinally thereof; and a breech-bolt supported in said chamber on said inwardly-struck ribs in relatively widely-spaced relationship to the inner wall thereof for longitudinal reciprocable movement in said chamber.

5. In a firearm the combination including: a receiver having a breech-bolt chamber; breech-bolt guide-means on the inner wall thereof said guide-means comprising circumferentially-spaced

parallel ribs consisting of metal struck inwardly from the exterior wall of said chamber and extending longitudinally thereof and bearing-surfaces extending longitudinally of said inwardly-struck ribs, said bearing-surfaces comprising concentric cylindrical surfaces of revolution of substantially-equal area and radius, the radius of each concentric surface being measured from the longitudinal axis of the receiver; and a breech-bolt supported in said chamber on the said bearing-surfaces of said inwardly-struck ribs for longitudinal reciprocable movement in said chamber.

6. In a firearm the combination including: a receiver having a breech-bolt chamber; breech-bolt guide-means on the inner wall of said chamber comprising longitudinal circumferentially-discontinuous bearing-surfaces struck inwardly from the exterior wall of said chamber and arranged to form longitudinal circumferentially-spaced grooves in the exterior wall of said chamber; and an element of the receiver constructed and arranged to be attached to the exterior wall of said chamber by cooperative engagement of said element with the said longitudinal circumferentially-spaced exterior grooves thereof.

7. In a firearm the combination including: a receiver having a breech-bolt chamber; breech-bolt guide-means on the inner wall of said chamber comprising longitudinal circumferentially-spaced ribs struck inwardly from the exterior wall of said chamber and arranged to form longitudinal circumferentially-spaced grooves in the exterior wall of said chamber; a trigger-plate; and means to attach said trigger-plate to said receiver comprising elements of said trigger-plate arranged to engage in the said longitudinal circumferentially-spaced grooves in the exterior wall of said chamber.

8. In a firearm the combination including: a receiver having a breech-bolt chamber; breech-bolt guide-means on the inner wall of said chamber comprising circumferentially-spaced ribs struck inwardly from the exterior wall of said chamber and arranged to form longitudinal circumferentially-spaced grooves in the exterior wall of said chamber; a trigger-plate; means to attach said trigger-plate to said receiver comprising resilient spaced-parallel lips on the upper edges of said trigger-plate arranged to snap into the said longitudinal circumferentially-spaced grooves in the exterior wall of said chamber; and fastening-means to secure said trigger-plate to said receiver against longitudinal movement with respect thereto.

9. In a firearm the combination including: a receiver having a breech-bolt chamber; breech-bolt guide-means on the inner wall of said chamber said guide-means comprising circumferentially-spaced ribs struck inwardly from the exterior wall of said chamber and arranged to form longitudinal circumferentially-spaced grooves in the exterior wall of said chamber; a breech-bolt supported on said circumferentially-spaced ribs for longitudinal reciprocable movement in said chamber; and a trigger-plate constructed and arranged to be attached to the exterior wall of said chamber by cooperative engagement with the said longitudinal circumferentially-spaced grooves thereof.

10. In a firearm the combination including: a receiver having a breech-bolt chamber; breech-bolt guide-means on the inner wall of said chamber said guide-means comprising circumferentially-spaced ribs struck inwardly from the ex-

terior wall of said chamber and arranged to form longitudinal circumferentially-spaced grooves in the exterior wall of said chamber; a breech-bolt supported on said circumferentially-spaced ribs for longitudinal reciprocable movement in said chamber; a trigger-plate; and means to attach said trigger-plate to said receiver comprising resilient spaced-parallel lips on the upper edges of said trigger-plate arranged to snap into the said longitudinal circumferentially-spaced grooves in the exterior wall of said chamber.

11. In a firearm the combination including: a receiver having a breech-bolt chamber; breech-bolt guide-means on the inner wall of said chamber said guide-means comprising circumferentially-spaced ribs struck inwardly from the exterior wall of said chamber and arranged to form longitudinal circumferentially-spaced grooves in the exterior wall of said chamber; a breech-bolt supported on said circumferentially-spaced ribs for longitudinal reciprocable movement in said chamber; a trigger-plate; means to attach said trigger-plate to said receiver comprising resilient spaced-parallel lips on the upper edges of said trigger-plate arranged to snap into the said longitudinal circumferentially-spaced grooves in the exterior wall of said chamber; and fastening-means to secure said trigger-plate to said receiver against longitudinal movement with respect thereto.

12. In a firearm the combination including: a receiver; a bushing in the forward end of said receiver, said bushing being arranged to form a forward breech-bolt chamber of reduced diameter and the portion of said receiver rearwardly

5 of said bushing constituting a rearward breech-bolt chamber of relatively-large diameter; breech-bolt guide-means on the inner wall of said rearward chamber comprising circumferentially-spaced parallel ribs extending longitudinally thereof; abutments at the forward ends of said ribs for engagement by the rear end of said bushing; and a breech-bolt adapted to be mounted in said forward and rearward chambers for reciprocable movement therein, said breech-bolt having a reduced substantially-cylindrical forward end arranged to be slidably supported on the inside wall of the forward chamber of said receiver and an enlarged substantially-cylindrical rear end arranged to be slidably supported only by the longitudinally-extending ribs of the rearward chamber of said receiver.
